UNITED STATES PATENT OFFICE.

HARRY B. STILZ, OF SEATTLE, WASHINGTON.

OIL-BURNER.

No. 799,949.

Specification of Letters Patent.

Patented Sept. 19, 1905.

Application filed February 28, 1905. Serial No. 247,648.

To all whom it may concern:

Be it known that I, HARRY B. STILZ, a citizen of the United States, residing at 1015 East Columbia street, Seattle, in the county of King and State of Washington, have invented a new and useful Oil-Burner, of which the following is a specification.

My invention relates to improvements in oil-burners in which the oil is reduced to an atomized state on issuing from a nozzle preparatory to its combustion in a supply of fresh air from an outside source; and the objects of my improvement are, first, to supply a burner which will completely burn an oil consisting of a mixture having various densities and boiling points, such as crude petroleum, without the use of an external atomizing agent, such as compressed air or steam; second, to provide a means for boiling off the more volatile constituents of the oil and separating the vapors generated, these vapors to be used in atomizing the oil remaining when the two are brought together in a suitable nozzle; third, to furnish a means of generating the vapor at a rate automatically kept equal to the rate at which such vapor is used in the nozzle; fourth, to regulate the pressure within the system, and hence the intensity of the flame from the nozzle, by means of a relief-valve in the oil-supply pipe between the pump and the vaporizer. I attain these objects by the system illustrated in the accompanying drawings, in which—

Figure 1 is a plan view, and Fig. 2 is an elevation.

The oil is pumped from the supply-tank T into the vaporizer H by means of the pump P, operated mechanically from an external source. The burner E supplies heat to the vaporizer, so that when the oil circulates through the coils c from the bottom and into the top of the cylinder O the more volatile constituents are vaporized by the heat from said burner. The vapors collecting in the top of the cylinder O force the surface of the oil therein to a lower level, the surplus oil escaping to the pressure-reservoir R until a determined pressure is produced by the air compressed above the oil in said reservoir, when the relief-valve V will open, and the surplus oil escapes into the supply-tank T. When the cylinder O becomes full of vapor, no oil can enter the coil c and no more vapor is produced. As the vapor is carried off from the top of the cylinder O for use the reduced pressure thereby will permit the oil to enter at bottom, and on pass-

ing through the coil a part of same will be vaporized as before. The vapor thus separated is entered into the nozzle N through the pipe f, being superheated in its passage down through the vaporizer H. The oil, deprived of its more volatile parts, enters the nozzle through the pipe g, and on passing through the small opening at the center of the nozzle is met by the rapidly-moving vapors. 65 The mixture on escaping from the nozzle enters the furnace in a thoroughly-atomized state along with a supply of air induced by the high velocity of the jet from the nozzle, complete combustion taking place on ignition. By varying the pressure at which the relief-valve V operates the pressure of the atomizing-vapors will be regulated to correspond, hence a changeable rate of supply from nozzle. 75

The burner e derives its supply of combustible from the vapor-pipe f, and an auxiliary means will be provided for heating the vaporizer at start.

The vaporizer is inclosed in an insulating-casing I, provided with an opening at the bottom for the entrance of the vaporizing-flame and with an opening at the top for the escape of the products of combustion from said flame. The cylinder O is located near the coil inside 85 the casing; but the pressure-reservoir R is located on the outside, where it will not be affected by the heat.

I prefer to show the system described as being a general case. For a burner used under a boiler the vaporizer would consist of coils c and cylinder O, placed inside the furnace at a location giving the proper temperature to generate the desired amount of vapor, an auxiliary heater being provided for 95 the vaporizer to start the process.

The mechanically-operated pump could be omitted by placing the supply-tank T at a height above vaporizer sufficient to produce the desired pressure by the head of oil. With 100 the supply-tank so located the pressure-reservoir R and the relief-valve V would also be omitted as being unnecessary.

When the oil is to be atomized in a space under a high pressure, as inside the cylinder 105 of an internal-combustion engine, the mechanically-operated pump and the system substantially as described will be required. The vaporizing in this case, however, can be effected by the heat from the exhaust-gases from the 110 engine being made to pass through the vaporizing-chamber.

I am aware that prior to my invention oil-burners have been made in which the oil is atomized for combustion. I therefore do not claim such a burner broadly; but

5 What I do claim as my invention, and desire to secure by Letters Patent, is—

1. In an oil-burner the combination of an atomizing-nozzle, a vaporizer provided with a chamber for containing oil and the vapor 10 generated therefrom, a means of supplying oil to said chamber, a means of supplying heat to the vaporizer, a conduit for conveying oil from the bottom of said chamber to the atomizing-nozzle and a conduit for conveying vapor from 15 the top of said chamber to the atomizing-nozzle.

2. In an oil-burner the combination with an atomizing-nozzle, a vaporizer provided with a chamber for containing oil and the vapor 20 generated therefrom, a means of supplying heat to the vaporizer and conduits from the top and bottom of said chamber to the atom-

izing-nozzle, of a pump for supplying oil to the vaporizer under pressure, an auxiliary reservoir in the form of an air-chamber communicatively connected at its bottom with the oil-supply pipe to vaporizer and a relief-valve in said oil-supply pipe.

25

3. In an oil-burner the combination with an atomizing-nozzle, of a cylinder with coils of 30 pipe external to same and connected thereto near the upper and lower ends thereof, a means of supplying oil under pressure to said cylinder and coils, a means for conveying vapor and oil from said cylinder to the atomizing-nozzle, and a means of heating said coils and said cylinder all substantially as set forth.

35

In testimony whereof I have signed my name to this specification in the presence of two subscribing witnesses.

HARRY B. STILZ.
